UNITED STATES PATENT OFFICE.

BURT W. LUNDY AND JOHN V. GIDDENS, OF VALDOSTA, GEORGIA.

AUTOMATIC AIR-BRAKE.

1,247,121.

Specification of Letters Patent. Patented Nov. 20, 1917.

Application filed August 11, 1914. Serial No. 856,196.

To all whom it may concern:

Be it known that we, BURT W. LUNDY and JOHN V. GIDDENS, citizens of the United States, residing at Valdosta, in the county 5 of Lowndes and State of Georgia, have invented new and useful Improvements in Automatic Air-Brakes, of which the following is a specification.

This invention is an improved automatic 10 air brake apparatus for use on a railway car or locomotive to automatically operate the air release valve in the event that the car should leave the track or should drop on either side by the breaking of a wheel, 15 axle or for other reason, the object of the invention being to provide improved air brake apparatus of this kind which may be readily attached to any ordinary railway car, which can only be operated in the event 20 of an accident and which is not likely to get out of order.

The invention consists in the construction, combination and arrangement of devices hereinafter described and claimed.

25 In the accompanying drawings:—

Figure 1 is a transverse sectional view of the portion of a railway car provided with automatic air brake apparatus constructed in accordance with our invention.

30 Figs. 2 and 3 are detail views of the relief valve.

Fig. 4 is a view similar to Fig. 1 and showing a modification.

For the purposes of this specification a 35 part of a railway car is indicated at 1 provided with the usual train pipe 2 of the usual air brake apparatus. One of the cross beams of the car is indicated at 3 and the bolster of one of the trucks is indicated at 4. Our improved apparatus for automatically applying the brakes when the car leaves the track or breaks down is provided for each truck and consists of a relief valve 5 and operating connections therefor hereinafter described. One of the valves is employed in connection with each car truck and comprises a casing 6 which is connected to the train pipe and a branch pipe 7 and a plug 8 which is adapted to turn in the 50 casing in either direction in order to open an air port 10 and thereby effect a reduction of pressure in the train pipe and hence cause the brakes to be applied, but the said plug, is normally in intermediate position to prevent air from being discharged from the 55 train pipe.

The plug of the valve is provided with ratchet disks 13—14 and is also provided with a pair of oppositely extending levers 15—16 which are pivotally mounted on the 60 stem of the plug and are respectively provided with pawls 17—18 for coaction with said ratchet disks in turning the plug. Each pawl is provided with a spring 19 to keep it in normally engaged position. A rock 65 arm 20 is mounted on a stub shaft 21 with which the valve casing is provided and is held in normal position by a coiled spring 22. A spring 23 connects said rock arm to the lever 15. An arm 24 projects from the 70 valve casing and is connected by a spring 25 to the lever 16. These springs normally hold the levers in inoperative position so that the valve remains closed and said levers cannot be operated excepting by the 75 means hereinafter described. In the form of our invention shown in Fig. 1 in which the brakes are automatically applied if a wheel or an axle breaks in one of the trucks, or the car body turns to one side or other 80 as the result of any accident, the beam 3 and the bolster 4 are respectively provided with oppositely extending vertical arms 26—27. A bell crank lever 28 is associated with the arm 26 and lever 15 and a bell 85 crank lever 29 is associated with the arm 27 and the lever 16, said bell crank levers being pivotally connected to said arms and respectively pivotally mounted on the bolster and beam as at 30—31. One arm of 90 each bell crank lever is engaged with one side of its associated valve lever to move said valve lever against the tension of its spring in the event that the car body assumes an abnormal angular relation to the 95 bolster as the result of the car dropping on one side by the breaking of a wheel or axle or for any other reason which might cause a dangerous accident. Should the car body be thus inclined or the truck dropped on 100 one side from any cause the resulting angular movement of the cross beam 3 with relation to the bolster 4 will exert an endwise thrust on the arms 26—27 which will cause the bell crank levers to turn on their 105 pivots and thereby cause the valve levers or one of them to be turned on the stem of the plug against the tension of its spring so as to cause the pawl to slip idly on one of the ratchet disks and engage behind a 110 tooth thereof and whereupon the spring connected to said arm will return the same

to its initial position and hence cause said pawl to coact with said ratchet disk to partly turn the valve plug to open the valve and thereby relieve pressure in the train 5 pipe and hence cause the brakes to be applied throughout the train.

In the form of our invention shown in Fig. 4 the bell crank levers 28^a—29^a are respectively associated with vertically movable trip bars 32—33 which are arranged in suitable guides and supports 34 with which the bolster of the truck is provided. Said bell crank levers and trip bars may, in practice, be bent as indicated in said 15 figure of the drawing to afford clearance, and in practice, the outer ends of said bell crank levers are broadened to permit them to slip on the upper ends of the trip bars and compensate for the pivotal movement 20 of the truck when going around curves and prevent stress from being imposed on said levers and trip bars. Should a wheel or axle break or the truck drop on either side or the car body turn to an abnormal angle 25 with respect to the bolster as the result of any accident, the trip bar on the lower side of the truck will strike on the rail, an upward thrust will be imparted thereto and

hence the associated bell crank lever will be turned and said bell crank lever will release one of the levers of the relief valve and hence cause the brakes to be applied throughout the train. 30

Having thus described our invention, we 35 claim:—

In air brake apparatus a relief valve including a turning plug having a ratchet disk, a lever pivotally mounted on said plug and having a spring pressed pawl engaging the ratchet disk, a spring connected to said lever to normally hold the same against movement, a pivotally mounted bell crank having an arm associated operatively with said valve lever and truck carried means to turn said bell crank and cause the latter 40 and the lever to open the valve when the truck assumes an abnormal angular position with respect to the car body. 45

In testimony whereof we affix our signatures in presence of two witnesses.

BURT W. LUNDY.
JOHN V. GIDDENS.
